UNITED STATES PATENT OFFICE

EDMUND BURKE, OF PORTLAND, MAINE, ASSIGNOR TO BROWN COMPANY, OF BERLIN,
NEW HAMPSHIRE, A CORPORATION OF MAINE

MULTIPLE CONDUIT

Application filed October 7, 1926. Serial No. 139,977.

This invention relates to sections of multiple conduit which are built up of sections of single conduit secured in definite spaced relation. While the single conduit of which the assembly is composed may be of any desired material, I prefer to use waterproofed fibrous conduit on account of its qualities including lightness, cheapness, strength and toughness, which makes it especially suitable for many of the uses in which conduit is commonly employed, but it is to be understood that the invention contemplates single conduits of any material whatever, and resides in the manner of securing the conduits together into a multiple unit.

For a more complete disclosure of my invention, reference is had to the drawing, of which,—

Figure 1 is a perspective of a section of multiple conduit illustrating an embodiment of my invention.

Figure 2 is a transverse sectional view of two of the conduit assemblies in superposed relation.

Referring to the drawing in detail, 10 represents sections of single conduit of any desired material and cross sectional size and shape. The conduits 10 may be of any desired number and arranged in any desired manner. For convenience, an assembly of four single conduits of ordinary tubular shape is shown. The conduits are held in place by spacing means which comprise mold-
ed or cast blocks 11 preferably of a shape approximating that shown on the drawing, these blocks being spaced at proper intervals along the conduits and surrounding each single conduit completely. The molds necessary to form blocks of the kind illustrated are not shown as they obviously could be constructed without difficulty by any one skilled in the art. The molds necessarily hold the conduits firmly in correct spaced relation while the plastic or molten block-forming material is introduced into the molds and allowed to set. The material used for the blocks may be of any kind capable of being molded or cast. I prefer for this purpose a concrete mixture of Portland cement and cinders, the concrete being reinforced as usual

if desired. The use of cinders, ashes or equivalent material, makes the concrete comparatively light and thus suitable for use with fibrous conduit which is also light. The resulting multiple unit is thus both light and strong.

In forming the blocks, the sections of single conduit are arranged in substantially parallel relation and held in position by suitable concrete molds while the concrete is poured in and allowed to set. The molds are preferably constructed so that the thickness of concrete from a conduit to the outer face of a block (as at 13) is just half the thickness between adjacent conduits (as at 12). As a result of this construction, when multiple units are placed side by side, or in superposed relation, as shown in Figure 2, all the conduits in the group will be uniformly spaced. The concrete blocks, besides holding the single conduits in properly spaced relation, also bond them together firmly against relative longitudinal motion. When conduit is used for telephone or other cables, the cables have to be drawn through after the conduit has been laid. Frequently, the pull required to drag a long heavy cable through a conduit is very great and it is evident that practically all the reactive force to such a pull is the friction on the walls of the conduit. As this reactive force tends to move the conduit longitudinally, it is highly important that the conduit be securely anchored against such motion. This is accomplished by the blocks which in setting, closely engage the conduits and grip them firmly.

Having thus described an embodiment of my invention, it should be evident to those skilled in the art that various changes and modifications may be made without departing from its spirit or scope as defined by the appended claims.

I claim:—

1. As a new article of manufacture, a section of multiple conduit comprising a plurality of single lengths of single conduit in substantially parallel spaced apart relation, and means for holding said single conduits in relative position, said holding means comprising a plurality of blocks of solidified

plastic material formed around and between said single conduit sections, said blocks being spaced longitudinally of the sections, the thickness of each block being a small fraction of the length of the conduit section.

2. As a new article of manufacture, a section of multiple conduit comprising a plurality of single lengths of single conduit arranged in rows in substantially parallel

10 spaced apart relation, the spacing between the single sections being substantially uniform, and a plurality of blocks spaced longitudinally of the sections, each block being formed around and between all said single sections with a thickness equal to a small fraction of the length of the conduit section and extending outwardly beyond the single sections for a distance equal to half that between adjacent sections.

20 3. As a new article of manufacture, a section of multiple conduit comprising a plurality of sections of single conduit arranged in substantially parallel spaced apart relation, and spacing blocks of concrete formed around and between said single sections, said blocks having a thickness equal to a small fraction of the length of the conduit section and being spaced from the ends of the section and from each other.

30 4. As a new article of manufacture, a section of multiple conduit comprising a plurality of single conduits in parallel uniformly spaced relation, and a plurality of spacing blocks of concrete extending around and between said conduits, the thickness of the concrete between a conduit and the outer surface of a block being substantially one half the thickness between adjacent conduits.

5. As a new article of manufacture, a section of multiple conduit comprising a plurality of sections of single conduit arranged in substantial parallelism and spaced apart, and longitudinally spaced blocks of concrete molded about said single conduits, the dimension of each block in the direction of the length of the conduits being less than its overall dimensions in directions transverse with respect to the conduit.

6. As a new article of manufacture, a section of multiple conduit comprising a plurality of sections of single conduit arranged in substantial parallelism and uniformly spaced from each other, and a plurality of blocks of concrete molded around said sections at spaced points therealong, the spaces between the blocks being greater than the thickness of the blocks, each block having a thickness which is small compared to the length of the conduit section.

60 7. In testimony whereof I have affixed my signature.

EDMUND BURKE
